CLAIM

The ornamental design for a table top, as shown and described.

DESCRIPTION

FIG. 1 is a top right front perspective view of a table top showing my new design. The broken lines are for illustrative purposes only and form no part of the claimed design;

FIG. 2 is a front elevational view thereof; the left side elevational view, right side elevational view and rear elevational view being a mirror image;

FIG. 3 is a top plan view thereof;

FIG. 4 is a bottom plan view thereof; and,

FIG. 5 is a cross-sectional view thereof along line 5—5 of FIG. 4.
